UNITED STATES PATENT OFFICE.

THOMAS DOLINAR, OF PINEY FORK, OHIO.

CHURN.

1,373,313.

Specification of Letters Patent. Patented Mar. 29, 1921.

Application filed July 15, 1920. Serial No. 396,515.

To all whom it may concern:

Be it known that I, THOMAS DOLINAR, a citizen of Jugo-Slavia, residing at Piney Fork, in the county of Jefferson and State 5 of Ohio, have invented certain new and useful Improvements in Churns, of which the following is a specification.

This invention relates to certain new and useful improvements in churns.

10 The primary object of the invention is to provide a manually operable churn embodying a receptacle section and a dasher section with the latter supported upon a vertically adjustable frame whereby the dasher 15 may be removed from the receptacle by the elevation of the frame.

A further object of the invention resides 20 in the provision of a vertically adjustable frame for supporting a dasher operatively positioned within a churn receptacle, rack 25 and pinions being associated with each side of the frame for simultaneous operation to elevate the frame and dasher supported thereby.

25 With the above and other objects in view, the present invention consists in the novel form, combination and arrangement of parts hereinafter more fully described in connection with the accompanying drawings, and 30 in which like reference characters indicate similar parts throughout the several views.

In the drawings,

Figure 1 is a front elevational view of a churn constructed in accordance with the 35 present invention showing the dasher supported on the vertically adjustable frame with the rack and pinion devices for raising and lowering the frame,

Fig. 2 is a side elevational view, partly 40 broken away,

Fig. 3 is a horizontal sectional view taken on line III—III of Fig. 1 showing the pin wheel meshing with the lantern gear,

Fig. 4 is a cross sectional view taken on 45 line IV—IV of Fig. 1, showing the radial arms of the dasher within the churn receptacle,

Fig. 5 is a cross sectional view taken on line V—V of Fig. 1, showing the supporting 50 feet for the churn receptacle,

Fig. 6 is a vertical sectional view taken on line VI—VI of Fig. 1, showing the lantern gear keyed to the dasher shaft and

Fig. 7 is a perspective view of one of the 55 cover sections removed from the churn receptacle.

Referring more in detail to the accompanying drawings, there is illustrated a manually operable churn embodying a cylindrical receptacle 1 supported at its lower 60 end upon angle feet 2 and 3 and secured thereto by suitable fastening devices. The open upper end of the receptacle 1 is closed by a cover formed of semi-circular sections 4 having registering axial openings 5 cut 65 upon the chordal line thereof to accommodate the passage of the dasher shaft while adjacently positioned handles 6 are carried by the cover sections 4 to project laterally of the receptacle 1 as shown in Figs. 2 and 70 7 to facilitate the removal of the cover sections.

The dasher and shaft are supported on a frame that is adjustably mounted upon the receptacle 1, the frame being of inverted 75 U-shaped form embodying side legs 7 and 8 and upper transverse connecting bars 9. Two pairs of guide straps 10 are diametrically secured to the upper end of the receptacle 1 in vertical alignment with the supporting feet 3, while spaced bars 11 extend between each pair of straps as shown in Fig. 1. The lower ends of the frame bars 7 and 8 80 freely extend through the strap guides 10 as shown in Figs. 2 and 3 and are provided upon one face thereof with rack teeth 12 for purposes presently to appear.

To effect a vertical adjustment of the dasher supported frame, a shaft 13 is journaled beneath the receptacle 1 in the angle 90 feet 3 with a dasher gear 14 upon each end thereof. A vertical shaft 15 is journaled at each side of the receptacle 1 in the horizontal portion of the angle feet 3. These shafts carry bevel gears 16 at their lower 95 ends in constant mesh with the bevel gears 14 while the upper ends of the shafts 15 are journaled in brackets 17 carried by the strap connecting bars 11 and are provided with bevel gears 18 upon the upper ends thereof. 100 A stub shaft 19 is horizontally journaled in each pair of strap bars 11 and is provided with a pinion 20 in mesh with the rack teeth 12 of the bars 7 and 8 while bevel gears 21 upon the shafts 19 mesh with the bevel gears 18 upon the shafts 15. The shaft 19 adjacent the frame bar 8 is provided with a wrench end 19' for rotating all of said gears and pinions in a manner to be later described.

The dasher and mounting therefor are more clearly shown in Figs. 1, 3, 4, and 6,

the dasher comprising a shaft 22 carrying agitating blades 23 upon the lower ends thereof while the upper end of the shaft is journaled within the arms 24 projecting inwardly from the frame arm 7 and overlying the receptacle 1. A nut 25 is secured to the upper end of the shaft 22 to retain the shaft rotatably mounted within the arms 24. As shown in Fig. 6, that portion of the shaft 22 extending between the arms 24 is rectangular in cross section and extends through the rectangular bore of the lantern gear 26 confined between the arms 24. A power shaft 27 is journaled in the arms 7 and 8 at a point above the arms 24 and carries a pin wheel 28 in mesh with the lantern gear 26 and rotated by the crank handle 29 upon the shaft 27.

In order to raise or lower the dasher 22 in the receptacle 1, a wrench is applied to the end 19' of the stub shaft 19 and rotation of the shaft 19 adjacent the arm 8 is directly communicated by the pinion 20 to the rack teeth 12. The meshing gears 18—21 and 14—16 communicate motion to the stub shaft 19 adjacent the arm 7 so that the side legs or arms 7 and 8 of the frame are simultaneously raised and lowered. The shaft 27 carrying the pin wheel 28 being rotated by the crank 29, communicates motion to the dasher shaft 22 by meshing with the lantern gear 26. The cover being formed of separable sections, access to the receptacle may be readily obtained while the relative depth

of the dasher within the receptacle is also 35 under the control of the operator.

While there is herein shown and described the preferred embodiment of the invention, it is nevertheless to be understood that minor changes may be made therein without departing from the spirit and scope of the invention as claimed.

What is claimed as new is:

A vertically adjustable mechanism supporting member comprising in combination 45 with a base support, a pair of horizontal stub shafts journaled at opposite sides of the support, a pinion fixed on each shaft, a gear on the outer end of each shaft, a pair of vertical shafts journaled at opposite sides 50 of the support, a gear on the upper end of each vertical shaft in mesh with the gear on the end of the adjacent stub shaft, a horizontal shaft journaled in the base support, meshing gears on the adjacent ends of the 55 horizontal shaft and the lower ends of the vertical shafts, an inverted U-shaped mechanism supporting member adjustable on the support, rack bars carried by the supporting member engaged by said pinions, and a manually operable mechanism carried by the supporting member, one of the stub shafts being constructed to receive a crank arm for rotating all of the shafts to effect 60 raising and lowering of the mechanism supporting member.

In testimony whereof I affix my signature.
THOMAS DOLINAR.
